UNITED STATES PATENT OFFICE.

NELSON B. SLAYTON, OF ALFRED CENTRE, NEW YORK.

HANDLE FOR COMBS.

SPECIFICATION forming part of Letters Patent No. 230,443, dated July 27, 1880.

Application filed February 21, 1880.

To all whom it may concern:

Be it known that I, NELSON B. SLAYTON, of Alfred Centre, in the county of Allegany and State of New York, have invented certain Improvements in Handles for Combs and other Portable Instruments of a Similar Character, of which the following is a specification.

This invention relates to improvements in the handles of pocket-combs, or combs intended to shut up so as to be conveniently carried, the said improvements being also adapted to many forms of pocket instruments.

In a patent granted to me October 7, 1879, No. 220,438, I described and claimed a razor or knife provided with a handle in many respects resembling that herein described, and I wish it understood that what was therein shown I make no claim to here.

In the drawings which serve to illustrate my invention, Figure 1 is a side elevation, showing the comb closed or shut into the handle. Figs. 2 and 3 show the same partly and fully open. Figs. 4 and 5 are cross-sections of the instrument as shown at *xx* in Fig. 1, the former looking toward the joint or hinge and the latter toward the butt of the handle. Fig. 6 is a cross-section of a modification, which will be more fully hereinafter described.

Let A represent an ordinary comb provided with a back, B, preferably of sheet metal, and consisting of a tubular or solid rib and jaws to clasp the comb. The broader end of the back is slotted at *a* to receive the hinging-rivet, as indicated by dotted lines in Figs. 1 and 3. I may, however, make the comb and back all in one piece and of the same material, and construct the slot *a* in the comb itself; or any part of the back may be made of or covered with metal, if desired.

The handle consists of two cheeks, C C, and a tubular, or partly tubular, back, D, all preferably formed from one strip or plate of sheet metal. To the end of the handle is attached a butt, E, containing a socket, *b*, to fit the rib or cylindrical part of the back B of the comb.

When the comb is shut, as in Fig. 1, the rib or cylindrical part of the back of the comb rests in the socket *b* in the butt E, and when the comb is to be opened it is slipped length-

wise until free from this socket and then partially opened, as shown in Fig. 2. The comb is now slipped forward on the hinging-rivet until its butt clears the end of the handle, when it is turned completely open and socketed, as shown in Fig. 3. This is done by causing the rib on the back B of the comb to engage the tubular back D of the handle, which is large enough to receive it. These same means of staying the hinged part when open by causing it to enter a socket in the handle is shown in my patent before mentioned, and I make no claim to it here.

The handle is constructed, as before stated, of sheet metal, and the edges of the cheeks C are turned up, as at *c*, to give an apparent thickness to the same. The recess formed by this means between the flange *c* and the tubular back D may then be filled by a plate, F, which can be ornamented, if desired.

It will be seen that the plate F serves to stiffen the cheeks C C and to hide the rivet which hinges the comb, and it may be secured to the cheeks by soldering, or by any other known means. The butt E may also be chased or otherwise ornamented, as indicated in Fig. 2.

If the handle, butt, and comb-back be made of brass or other soft metal, the sockets in the butt E and the tubular back D may be lined with a thin plate of steel to take the wear in socketing.

It is not important that the ribbed or tubular portions of the back and handle should be cylindrical, as shown in the first five figures. They may be of the form shown in Fig. 6, or of other forms as well.

Having thus described my invention, I claim—

1. A handle for a folding or pocket instrument having a butt, E, provided with a socket, *b*, in combination with the slot-hinged back B of the comb or other instrument, arranged to fit into the socket *b*, substantially as set forth.

2. The handle shown, consisting of the tubular or socketed back D and the cheeks C C, provided with turned-up flanges *c c*, all formed from one piece, substantially as set forth.

3. The handle shown, consisting of the tubular, or partly-tubular, back D, the cheeks C

C, provided with the turned-up flanges *cc*, and the attached plates F F, all arranged substantially as and for the purposes set forth.

4. The combination of the hinged part, provided with a slot, *a*, and ribbed back, the handle consisting of the tubular, or partly tubular, back D, cheeks C C, provided with flanges *cc*, between which cheeks the hinged part is pivoted, the butt E, containing the socket *b*,

and the plates F F, arranged as shown, all for the purposes set forth.

In witness whereof I have hereunto signed my name in presence of two subscribing witnesses.

NELSON B. SLAYTON.

Witnesses:

JOHN M. MOSHER,
R. STILLMAN.
